Design for a Carpet Pattern.

Patented Aug. 11-1863.

Application No. 6

Dec. 1810

Elmer G. Key of Lowell, Mass.
Assor to

Lowell Manufacturing Company.

Letters Patent No. 1810 - Dated Aug. 11th 1863.

The schedule referred to in these Letters Patent and making part of the same.

To all whom it may concern:

Be it known that E. Elmer G. Key, of Lowell, in the County of Middlesex, and State of Massachusetts, have originated and designed a new Pattern for Carpets or other fabrics, of which the following is a full, clear and exact description, reference being had to the accompanying drawings, making part of this specification.

In corner A, is one fourth of a large oblong set figure, composed of a block, narrow frame, ground work of small lines and blocks, and a double outside frame.

In corner B, is a figure similar to that of corner A. In corner C, is one fourth of a set figure resting on a ground of regular work, enclosed by the broad oval frame 5, which supports four large scroll figures.

In corner D, is one fourth of a group of leaves and small lines enclosed by the oval frame 6, which also supports four large scroll figures. It is an oblong block resting on the broad band 7, which is composed of short lines, blocks and three series of key work. The remainder of the design consists of a diamond ground work. The figures of corners C and D, are similar to those of the corresponding in Design designated as Application U. S. No. 1631, for which Letters Patent were granted Aug 12th 1862.

The colors employed for the different portions of the design may be varied to suit the taste and wish of the manufacturer.
